[57] CLAIM

The ornamental design for headboard/footboard, as shown and described.

DESCRIPTION

FIG. 1 is a perspective view of a headboard/footboard, showing the footboard of our new design;
FIG. 2 is a top plan of the footboard of FIG. 1;
FIG. 3 is a front elevation of the footboard of FIG. 1;
FIG. 4 is a side elevation of the footboard of FIG. 1, with the opposite side elevation thereof being a mirror image thereof;
FIG. 5 is a perspective view of a headboard/footboard, showing the headboard as an alternate embodiment;
FIG. 6 is a top plan of the headboard of FIG. 5;
FIG. 7 is a front elevation of the headboard of FIG. 5; and,
FIG. 8 is a side elevation of the headboard of FIG. 5, with the opposite side elevation thereof being a mirror image thereof.
